Primary Examiner—James R. Feyrer

[57] ABSTRACT

A variety of Kentucky bluegrass having a high level of disease resistance, excellent turf performance in the sun and shade and a medium level of seed yield potential.

1 Drawing Sheet

1

Kentucky bluegrasses have been disclosed in U.S. Plant Pat. No. 3,156 which issued on May 9, 1972; U.S. Plant Pat. No. 3,186 which issued on May 23, 1972; U.S. Plant Pat. No. 4,336 which issued on Nov. 28, 1978; U.S. Plant patent application, Ser. No. 872,537, filed June 10, 1986; U.S. Plant patent application, Ser. No. 910,146, filed Sept. 19, 1986; and U.S. Plant patent application, Ser. No. 028,424, filed of even date herewith.

SUMMARY OF THE VARIETY

The present invention relates to a new and distinct variety of *Poa pratensis* which has been designated Ba 72-492 Kentucky bluegrass.

Ba 72-492 plant material originated by crossing a Kentucky bluegrass plant ("Gnome") disclosed in U.S. Plant patent application Ser. No. 872,537, the seed parent, with a pollen parent plant. As a result of this breeding, a distinct variety was produced and asexually propagated by rhizomes, tillers and disseminules. Seed of Ba 72-492 was produced first at Marysville, Ohio and later at Gervais, Oreg.

Asexual reproduction of Ba 72-492 by propagules (tillers and rhizomes) and by disseminules (modified caryopsis produced by apomixis) has consistently produced plants indistinguishable from the mother plant.

Ba 72-492 has a number of highly desirable characteristics including a good level of resistance to *Helminthosporium* spp that causes leaf spot, melting out and crown rot, *Ustilago striiformis* that causes stripe smut, *Erysiphe graminis* that causes powdery mildew, and *Puccinia* spp. that causes rust; an attractive leafy turf type growth habit; moderately wide leaf blades; an attractive green color which can be maintained throughout the entire growing season; good turf performance as evidenced by consistently high scores in tests throughout the U.S.A. and Canada; and a medium seed yield potential in the bluegrass seed production region of the U.S.A.

In comparison with its seed parent, Gnome, the new variety is more shade tolerant and has better resistance to powdery mildew and rust. In comparison to another Kentucky bluegrass (Ba 72-500) which is disclosed in U.S. Plant patent application Ser. No. 910,146 which also has Gnome as its seed parent, Ba 72-492 produces seeds that are shorter than Ba 72-500 and the panicle of Ba 72-492 does not nod as much as Ba 72-500.

2

BRIEF DESCRIPTION OF THE DRAWING

FIG. 1 is a photograph of Ba 72-492 Kentucky bluegrass plant in the vegetative stage including the extensive root and rhizome system;

FIG. 2 is a photograph of Ba 72-492 Kentucky bluegrass panicle; and

FIG. 3 is a photograph of Ba 72-492 Kentucky bluegrass seed.

DETAILED DESCRIPTION OF THE VARIETY

Ba 72-492 Kentucky bluegrass (*Poa pratensis* L.) is perennial with creeping rhizomes forming a moderately dense turf. When plants overwinter in the field with freezing temperatures and then are brought into the greenhouse during late winter to continue growth undisturbed by clipping under moderate temperatures (60°-80° F.), culms are erect averaging 486 mm in length with an average of 2.2 nodes per culm. The uppermost internode averages 10.5 cm, and the peduncle averages 12.6 cm in length and 0.552 mm in thickness. The flag leaf averages 5.2 cm in length, 3.6 mm in width and 0.117 mm in thickness. The panicle is generally erect as opposed to nodding with an average length of 12.6 cm, width of 4.2 cm, and 5.5 whorls. The lowest whorl has an average of 4.0 branches and the third whorl from the bottom of the panicle has an average of 3.0 branches. The average spikelet at the tip of a branch in the lowest whorl is 5.2 mm in length and has 4.4 florets with an outer glume of 2.9 mm and an inner glume of 3.3 mm in length. A similar spikelet from the third whorl from the bottom of the panicle is 5.0 mm in length and has 4.2 florets with an outer glume of 3.0 mm and an inner glume of 3.3 mm in length. After the seed has been conditioned, the lemma has a generally smooth keel and almost no long fine hairs at the base. The seed of Ba 72-492 is 2.53 mm in length and 0.76 mm in width with approximately 1,275,740 seeds per pound. Comparisons of Ba 72-492 with other bluegrass varieties on seed dimensions are shown in Table 1 and on seed numbers per pound are shown in Table 2.

TABLE 1

Seed Measurements of Ba 72-492 and Other Bluegrass Varieties After Conditioning

Variety	Length (mm)	Width (mm)
Ba 72-492	2.53	0.76
Ba 70-139	2.86	0.78
Ba 72-500	2.77	0.80
Baron	3.07	0.86

TABLE 1-continued

Since environmental conditions such as soil and climate may influence morphological characters to some extent, comparisons of morphological characteristics of Ba 72-492 are made with other Kentucky bluegrass varieties in Tables 3-7.

TABLE 3

Morphological Comparisons of Ba 72-492 and Other Bluegrass Varieties Grown As Unmoved Spaced Plants in the Field at Marysville, Ohio.		
Mature Plant Height 2 Year Mean	Leaf Blade Width Annual	Panicle Density 2 Year Mean
Ba 72-492	40	2.4

Rating Scale: Larger number indicates higher quality.

In addition, Ba 72-492 tolerates shady growing conditions very well which is an important characteristic that allows an even broader range of use. Comparisons of Ba 72-492 and other varieties for shade performance are found in Table 9 and Table 10.

The new variety has a pleasant medium green color which can be maintained throughout the growing season and widely scattered locations in the U.S.A. and Canada as shown by the comparative test results in Table 11.

Rating Scale: Larger number indicates darker green color.

Turf diseases are one of the major causes of inconsistent and poor turf performance among locations and years. Comparisons of resistance to leaf spot (also known as melting out and crown rot) caused by *Helminthosporium vagans*, powdery mildew caused by *Erysiphe graminis*, rust caused by *Puccinia* spp., dollarspot caused by *Sclerotina homeocarpa*, and red thread caused by *Corticium fuciform* are presented in Tables 12, 13, 14, 15, 16 and 17, respectively.

Rating: % of turf affected by disease

Tests in Maryland and Ohio indicate that Ba 72-492 is not highly susceptible to stripe smut caused by *Ustilago striiformis* since some unreleased selections of bluegrass had a high incidence of stripe smut but Ba 72-492 was not affected.

The new variety has a low growth habit and a slower vertical growth rate than many varieties and especially the common type of varieties such as Park, Kenblue and Newport, as indicated by comparisons in Table 18, which should allow it to tolerate lower mowing heights and possibly decrease the total number of mowings per year without sacrificing overall turf performance.

TABLE 18

Variety	Comparison of Growth Habit of Ba 72-492 and Other Bluegrasses at Marysville, Ohio.		
	Test 1 1 Year Mean ^a	Test 2 2 Year Mean ^a	Test 3 3 Year Mean ^b

TABLE 18-continued

Variety	Comparison of Growth Habit of Ba 72-492 and Other Bluegrasses at Marysville, Ohio.		
	Test 1 1 Year Mean ^a	Test 2 2 Year Mean ^a	Test 3 3 Year Mean ^b
LSD (.05)	0.3	0.5	12

^aRated 1-5, 5 = high growth, 1 = dwarf.^bRated as height (mm) of turf about one week after last mowing.

10 The leaf texture of Ba 72-492 is similar to many bluegrass varieties when maintained under mowed turf conditions as the comparisons show in Table 19.

TABLE 19

Variety	Comparison of Leaf Texture of Ba 72-492 and Other Bluegrasses Under Mowed Turf Conditions.		
	St. Louis Missouri	Agassiz British Columbia	Marysville Ohio
Ba 72-492	4.0	6.0	5.0

Victa	4.4		4.8
LSD (.05)	0.7		0.4

Rating: 1-9, 9 = finest texture.

Ba 72-492 has a medium level of seed yielding ability which should make it an economically feasible variety to produce for commercial markets as shown in Table 20.

TABLE 20

Variety	Seed Yield Comparisons of Ba 72-492 and Other Bluegrass Varieties in Oregon					
	Gervais			La Grande		
	Year 1	Year 2	Mean	Year 1	Year 2	Mean

Trampas						1194
LSD (.05)	140	134		149	181	220

Ratings: Pounds per acre of conditioned seed.

60 The low susceptibility of Ba 72-492 to rust and lodging under typical seed field conditions should aid in producing economical seed crops as noted by the comparative results on Table 21.

TABLE 21

Julia	4	5.0	4

Ratings

Rust: 1-4, 4 = very susceptible

Lodging: 0-5, 5 = severe lodging

What is claimed is:

1. A variety of Kentucky bluegrass plant, substantially as shown and described, characterized particularly by a high level of resistance to diseases, a desirable green color throughout the growing season, a high quality persistent turf under a wide range of environmental conditions including shady conditions and a medium level of seed yielding capacity.
